UNITED STATES PATENT OFFICE.

SIMON ANDERSON AND LEONARD HANSON, OF RUSSELL, MINNESOTA.

TANK-HEATER.

1,187,227.

Specification of Letters Patent. Patented June 13, 1916.

Application filed September 8, 1915. Serial No. 49,479.

To all whom it may concern:

Be it known that we, SIMON ANDERSON and LEONARD HANSON, citizens of the United States, residing at Russell, in the county of 5 Lyon, State of Minnesota, have invented certain new and useful Improvements in Tank-Heaters; and we do hereby declare the following to be a full, clear, and exact description of the invention, such as will enable 10 others skilled in the art to which it appertains to make and use the same.

The present invention is directed to improvements in tank heaters, and has for its object to provide a device of this character 15 which is adapted to be submerged in a tank to heat the water contained therein for live stock.

A further object of the invention is to provide a tank of this character which is constructed in such a manner as to furnish a maximum amount of heat with the use of a 20 small quantity of fuel.

A still further object of the invention is to provide a tank heater so constructed that 25 the draft to the fire box can be conveniently regulated, so as to insure proper consumption of the fuel.

With these and other objects in view, this invention resides in the novel features of 30 construction, formation, combination and arrangement of parts to be hereinafter more fully described, claimed and illustrated in the accompanying drawing, in which:

Figure 1 is a side elevation of the heater. 35 Fig. 2 is a longitudinal sectional view through the heater, showing the same submerged in a tank. Fig. 3 is a sectional view on line 3—3 of Fig. 1. Fig. 4 is a similar view on line 4—4 of Fig. 1.

Referring to the drawing 1 indicates the 40 body of the heater, one end of which terminates in an upwardly inclined hollow section 2, said section having one corner thereof associated with a plate 3, which provides 45 a duct 4, the purpose of which will appear later.

A grate 5 is provided, and is placed within 45 the body 1 with one edge resting against the outer wall of the section 2, said grate 50 being turned upwardly, as at 6, and is provided with hooks 7, which are adapted to engage over the projections 8 carried by the

side walls of the body, said grate having a cutaway portion 9 to accommodate the lower end of the duct 4.

A flue 10 has its lower end communicating with the interior of the body 1 through the top thereof, said flue having its lower end arranged above the pivotally supported damper 11. Slidable in an opening 12 formed in the flue 10 is a rod 13, said rod having its inner end connected to a wire strand 14, which is connected to the damper 11, said rod being also provided with a head 15, which serves to prevent the rod from dropping into the flue 10 when the damper is in its open position. It is obvious that when the rod is pulled outwardly, it will assume the position as shown in full lines, in Fig. 2, thus holding the damper in its closed 70 position.

Extending transversely through the body 1 is a passage 16, which permits water to circulate when the heater is in a tank, thus subjecting the water to the heat which passes 75 through the upper and lower chambers 17 and 18, which are produced by providing the passage 16.

Since the grate 5 is arranged directly under the lower end of the section 2, it is obvious that fuel can be fed to the grate as desired, and it will be further noted that the duct 4 will supply sufficient draft under the grate to insure proper burning of the fuel. Of course it will be obvious that the products of combustion can pass directly through the flue 10, upon opening the damper 11, and when the damper is closed it will be obvious that the heat will pass through the chambers 18 and 17.

The body 1 has secured to its bottom a pair of transversely disposed angle bars 19, which hold the body spaced from the bottom of the tank 20, thereby permitting water to circulate around the body 1. The upper end of the section is closed by a cover 21, and has pivotally connected thereto a damper 22, which is operable to regulate the draft through the duct 4.

What is claimed is:

A tank heater comprising a hollow body including a draft inlet section, a grate mounted in the body, a draft outlet pipe communicating with the interior of the body

adjacent the grate, a circuitous flue leading from said grate and communicating with the draft pipe, a damper hinged in the body adapted in one position to establish direct communication between the grate and draft pipe and in its other position to direct the products of combustion through said circuitous flue, a rod slidably supported by the pipe, and a wire connecting said rod and

damper and slidable to hold the damper in one or the other of its positions.

In testimony whereof, we affix our signatures, in the presence of two witnesses.

SIMON ANDERSON.
LEONARD HANSON
